Primary Examiner — Mary Ann Calabrese*Assistant Examiner* — Natalya M Rapundalo(74) *Attorney, Agent, or Firm* — McNees, Wallace & Nurick LLC(57) **CLAIM**

The ornamental design for a beverage dispensing apparatus, as shown and described.

DESCRIPTION

FIG. 1 is each a front view, a rear view, a right side view, and a left side view of a beverage dispensing apparatus, showing the design;

FIG. 2 is a top view thereof;

FIG. 3 is a bottom view thereof; and,

FIG. 4 is a perspective view thereof.

The broken lines in the drawings depict portions of the beverage dispensing apparatus that form no part of the claim.
